UNITED STATES PATENT OFFICE.

ALBERT HENRY, OF NEBRASKA CITY, NEBRASKA.

REGISTER.

1,369,027.

Specification of Letters Patent.

Patented Feb. 22, 1921.

Application filed August 20, 1920. Serial No. 404,949.

To all whom it may concern:

Be it known that I, ALBERT HENRY, a citizen of the United States, residing at Nebraska City, in the county of Otoe and State of Nebraska, have invented a new and useful Register, of which the following is a specification.

The device forming the subject matter of this application is an improvement in wooden registers of the type used in connection with cold air flues and for other purposes, the object of the invention being so to improve the register that the same may be removed readily for cleaning. The invention aims, further, to strengthen the register so that it will support an increased weight.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in top plan, a portion of a register constructed in accordance with the invention; Fig. 2 is a section taken approximately on the line 2—2 of Fig. 1; Fig. 3 is a section showing a modification; Fig. 4 is a section showing a further modification; and Fig. 5 is a section wherein another modification appears.

The numeral 1 denotes a marginal frame 1 ordinarily made of wood, sills 2 extending across the frame, and bars 3 extending across the frame at right angles to the sills 2, the sills and the bars being made of wood, and the sills 2 being recessed as shown at 4, to receive the bars 3.

In carrying out the present invention there is provided an edge binder, made of metal, and including a body 5 bearing against the outer surface of the frame 1.

The body 5 is outwardly extended and reversely bent as indicated at 6, to form an outwardly projecting double walled flange 7, the upper wall of the flange 7 being inwardly extended as indicated at 8, to overlap the upper edge of the frame 1. At its lower edge, the body 5 may be extended to form a lip 10 engaging the lower edge of the frame 1. The corner joints at the top of the edge binder, indicated at 9 in Fig. 1, may be closed by electric welding, by brazing or otherwise. Securing elements 11 pass through the part 8 and enter the frame 1. Securing elements 12 pass through the body 5 and through the frame 1 and enter the sills 2. The register may be supported on the outwardly extended flange 7 and the construction is such that the register is reinforced to support an increased weight. The register, further may be removed readily at any time, for cleaning.

In Fig. 3 of the drawings, parts hereinbefore described have been designated by numerals previously used, with the suffix "a". In Fig. 3, the edge binder is of double walled construction throughout. A securing element 14 may be used to attach the lip 10^a to the frame 1^a.

In Fig. 4 of the drawings, parts hereinbefore described have been designated by numerals previously used, with the suffix "b." In this form of the invention, a metal strip 15 is inserted between the constituent parts of the body 5^b.

In Fig. 5 of the drawings, parts hereinbefore alluded to are designated by numerals previously used, with the suffix "c." The edge binder shown in Fig. 5 is of the form shown in Fig. 3, saving for the fact that the lip 10^a of Fig. 3 is omitted.

Having thus described the invention, what is claimed is:—

1. A register comprising a marginal frame; and a binder including a body extended along the outer surface of the frame, the body being carried laterally and reversely bent to form an outwardly extended double walled flange prolonged across the upper edge of the frame.

2. A device of the class described, constructed as set forth in claim 1 and further

characterized by the fact that the lower edge of the body is prolonged to form a lip extended across the lower edge of the frame.

3. A device of the class described, constructed as set forth in claim 1 and further characterized by the fact that all portions of the binder are of double walled construction.

4. A device of the class described, constructed as set forth in claim 1 and further characterized by the fact that all portions of

the binder are of double walled construction, a strip being mounted between the constituent members of the body.

In testimony that I claim the foregoing 15 as my own, I have hereto affixed my signature in the presence of two witnesses.

ALBERT HENRY.

Witnesses:

MELVIN A. SHEPARD,
CHRISS PETERSEN.
